SLUG CATCHER

James F. Malcolm and Charles Winter, Hanover,
Pa., assignors to Revonah Spinning Mills,
Hanover, Pa.

Application July 31, 1940, Serial No. 348,958

1 Claim. (Cl. 28—64)

This invention relates to a slug catcher or detector for yarn and the like, and has for the primary object the provision of an efficient and inexpensive device of the above stated character which will be extremely easy to install and may be readily cleaned of lint and other foreign material to assure free passage of yarn therethrough and which will automatically detect and prevent the passing of an enlargement or defect in the yarn, frequently termed a "slug", beyond the device and consequently prevent defective yarn from being made up into yarn material.

Another object of this invention is the provision of a construction which may be readily and accurately adjusted for the passing of different size yarn therethrough and which may be easily threaded by one hand of the operator.

With these and other objects in view as will become more apparent as the description proceeds, the invention consists in certain novel features of construction, combination and arrangement of parts which will be hereinafter more fully described and claimed.

For a complete understanding of our invention, reference is to be had to the following description and accompanying drawings, in which

Figure 1 is a front elevation illustrating a "slug" catcher constructed in accordance with our invention.

Figure 2 is a side elevation, partly in section, illustrating the present invention.

Figure 3 is a top plan view illustrating the device.

Figure 4 is a fragmentary front elevation illustrating the device in the act of catching a slug in yarn.

Figure 5 is a sectional view taken on the line 5—5 of Figure 1.

Figure 6 is a sectional view taken on the line 6—6 of Figure 1.

Figure 7 is a sectional view taken on the line 7—7 of Figure 1.

Referring in detail to the drawings, the numeral 5 indicates an attaching bracket consisting of an arm 6 having integral with one end an attaching plate 7 and a supporting plate 8 integral with the other end. The arm 6 extends in an upwardly inclined plane to position the supporting plate 8 laterally of the attaching plate 7 and in a plane thereabove.

The attaching plate 7 is bolted or otherwise secured on a machine, a fragmentary portion of which is indicated by the character 9.

Detachably secured to the upper and lower

edges of the supporting plate 8 are guide eyes 10 of the split type and are reversely arranged to each other so that the yarn is brought into the lowermost eye from one direction and is brought into the uppermost eye from an opposite direction. The threading of the yarn into the eyes can be easily brought about by one hand of the operator.

A clamping plate 11 is detachably secured on the supporting plate between the eyes 10 by stud bolts 12 and is employed for removably and adjustably clamping on the supporting plate a guide bar or element 13 of elongated formation and of rectangular shape in cross section presenting flat faces thereto, any one of which may be readily brought into an operative position of guiding the yarn from one eye to the other eye.

Pivottally mounted on the supporting plate 8 are superimposed dogs 14 having serrated ends 15 disposed opposite the guide bar or element 13. The distance between the serrated ends and one face of the guide bar or element can be easily varied by adjusting the guide bar or element in the clamping plate towards and from the serrated ends of the dogs.

Stops 16 are arranged on the supporting plate 8 for limiting the downward pivotal movement of the dogs.

In setting up the device for operation, the space between the guide bar or element 13 and the serrated ends of the dogs when in engagement with the stops 16 is gauged to a size slightly larger than the external diameter of yarn so that the yarn may readily slide over the guide bar or element 13 until a defect or enlargement occurs in the yarn which is engaged by the lowermost dog and the latter is caused to swing upwardly and bind the yarn against the guide bar or element and thereby bring about breaking of the yarn preventing the defect from reaching the material being made up of the yarn. Should the defect pass the lowermost dog it will be engaged by the uppermost dog and thereby grip and bring about the breaking of the yarn.

The yarn during its travel through the present invention is continuously twisting or rotating about itself so that in some instances it is possible for slugs to pass free of the first dog owing to the slugs having flat sides. However, a large percentage of such slugs will be caught by the second dog. Further, it will be seen that the yarn travels in a straight course through the device and will not be distorted.

As the face of the guide bar or element wears the latter may have its position reversed on the

supporting plate so as to present another face opposite the serrated ends of the dogs.

A device constructed in accordance with the foregoing description and as shown in the drawings will be less liable to become choked from foreign matter, lint or the like and it will be noted that the yarn when removed therefrom leaves the device readily accessible to remove any lint or particles of foreign matter that may accumulate within the guide space between the serrated ends of the dogs and one face of the guide bar or element 13. Also, it will be seen that the device is extremely simple to adjust to accommodate yarn of different sizes and further that an operator through the use of one hand may readily thread the yarn rapidly through both eyes and between the serrated ends of the dog and the guide bar or element.

While we have shown and described the preferred embodiment of our invention, it will be understood that minor changes in construction, combination and arrangement of parts may be made without departing from the scope and spirit of the invention as claimed.

Having thus described the invention, what we claim is:

In a device of the character described, a ver-

tically arranged flat supporting plate, a mounting for said plate, split type eyes secured on said mounting above and below said plate and arranged in vertical alignment to guide yarn vertically relative to one of the vertical faces of said plate, superimposed gravity actuated dogs pivoted on said last mentioned vertical face of the plate, stops on said plate to limit the downward pivotal movement of the dogs and normally supporting said dogs on an inclined plane, a clamp member detachably secured to said plate, and an elongated vertically arranged guide member adjustably secured on the plate between the eyes by said clamp member and adjustable on the plate laterally of the eyes and towards and from the free ends of the dogs, said guide member being of rectangular shape in cross section providing a plurality of flat faces any one of which may be disposed opposite the free ends of the dogs and over which the thread passes between said eyes and relative to the free ends of the dogs, any one of said faces of said elongated guide member being capable of resting against the plate under the influence of said clamp member.

JAMES F. MALCOLM,
CHARLES WINTER.
